UNITED STATES PATENT OFFICE.

MAURICE B. BRAND, OF CHICAGO, ILLINOIS.

KEYLESS LOCK.

1,151,242.

Specification of Letters Patent. Patented Aug. 24, 1915.

Application filed August 19, 1914. Serial No. 857,467.

To all whom it may concern:

Be it known that I, MAURICE B. BRAND, citizen of the United States, residing at Chicago, in the county of Cook and State of Illinois, have invented certain new and useful Improvements in Keyless Locks; and I do hereby declare the following to be a full, clear, and exact description of the invention, such as will enable others skilled in the art to which it appertains to make and use the same.

My invention relates to keyless or so-called combination locks, its general object being to provide a simple and cheaply manufactured lock which may easily be manipulated for opening the same and which may also be easily re-set to a closure position.

A more specific object is to provide a lock having simple and effective guard and latch arrangements and adapted for use upon a milk-bottle holder, such as the one shown and described in my copending application filed June 27, 1914, as Serial No. 847,627.

While the locking mechanism of my invention may be used in a variety of positions and for many different purposes it is particularly adapted for such a purpose as the one shown in the above-mentioned application, and is shown in this embodiment in the accompanying drawings, in which—

Figure 1 is a fragmentary sectional view through the lock and a portion of the milk-bottle holder equipped with the same, with the mechanism in its normal locking position. Fig. 2 is a similar view showing the latch as moved to effect a movement of the guard from its normal position. Fig. 3 is a similar view showing the position of the parts when the latch is in its releasing position. Fig. 4 is a fragmentary horizontal section through the lock and milk-bottle holder along the line 4—4 of Fig. 1. Fig. 5 is a fragmentary plan view of the cover of the holder showing the actuating knob and the indicator carried thereby, together with the dial on the cover. Fig. 6 is an enlarged sectional view showing the spring means for preventing relative motion of the latch and the guard carried thereby.

In the embodiment of the drawings, the locking mechanism of my invention is shown as applied to a latch consisting of a bar 1 slidably mounted in the casing 2 of a milk-bottle holder equipped with a movable cover 3, said latch being also equipped with a hook 5, said latch being also equipped with a hook 3 adapted to engage a bale 6 suitably posi-

tioned within the said holder, the said latching member being normally pressed into the position shown in Fig. 1 by the engagement of a compression spring 7 with a shoulder 8 60 upon the latching member. The said latching member has a bifurcated inner end 19 extending through a slot in an auxiliary casing 10 housing portions of the mechanism of the lock. Pivotedly mounted in the said casing 10 and extending through the top of the cover 5 is a shaft 11 equipped at its upper end with a knob 12 for manually rotating the said shaft and also equipped with a pointed indicator 13, which indicator 70 operates with suitably numbered figures on the outer surface of the cover to indicate the relative position of the rotating shaft, as shown in Fig. 5.

Rigidly mounted upon the shaft 11 and 75 housed by the casing 10 is a disk 14, the periphery of which disk is normally disposed close to (but out of contact with) the end 19 of the slidably mounted latching member, which end presents a shoulder 25, toward the adjacent edge of the disk. Formed from the disk 14 and extending radially therefrom at different heights above the plane of said disk are prongs 15 and 16. 80 Movably mounted upon the latching member 1 (as for example by means of a pivot 17) is a guard 18, which guard also extends through the said slot in the auxiliary casing and is equipped at its inner end with a pair 85 of cam formations 19 and 20 extending at 90 acute angles to the axis of the bar 1. The guard 18 is also equipped at the juncture of the said cam surfaces with a slot 21, which slot is adapted to align with a similar slot in the latching bar 1 when the guard is in a 95 position in which its shank extends parallel to the axis of the bar 1, that is to say parallel to the cover 9 of the bottle holder. One of the forks presenting the said cam surfaces upon the guard is preferably equipped with 100 a toe portion 22 adapted to abut against the bottom of the auxiliary casing 10 so as to afford a stop for limiting the relative movement of the guard about its pivotal mounting 17, the said movement being restricted by suitable friction means associated 105 with the bar 1 and the latching member 18, such as a spring 23.

When the lock is to be operated so as to move the same from the locking position of Fig. 1 to the releasing position of Fig. 3, the latching bar 1 is first slid slightly in-

wardly of the casing by pressing a finger against the free end of the said bar. If this sliding motion is undertaken with the mechanism in position of Fig. 1, the end 19 of 5 the bar 1 will abut against the periphery of the disk 14, so as to prevent any step being taken toward the unlocking. However, if the dial member of the lock has first been turned to bring the member 15 into alinement with the sliding latch member (as shown in both Figs. 2 and 4, the slot produced in the periphery of the disk 14 by forming the prong 15 therefrom will permit the end 9 of the latching member to be slid 10 inwardly beyond the periphery of the disk 14, thereby bringing the prong 15 into forcible engagement with the cam surface 19, whereupon the said cam surface will cause the guard 18 to move about its pivotal 15 mounting into the position of Fig. 2. Then upon releasing the digital pressure on the free end of the bar 1, the spring 7 will protract the same, thereby drawing the end 9 of the latching member out of the said peripheral opening in the disk under the prong 15. Now if the indicating member is further rotated so as to bring the lower prong 16 into alinement with the axis of the latching member 1, this prong will then be directly 20 opposite to the said alined slots in the guard and the latching member. Consequently, upon again digitally sliding the latching member 1 inwardly, the said alined slots will house the prong 16 as shown in Fig. 3, there- 25 by permitting the latching member to be slid sufficiently to release the bale 6, as also shown in Fig. 3, thus permitting the milk-bottle holder to be opened. After the holder has been opened and again closed, it will be 30 evident that the friction spring 23 would maintain the guard in its releasing position; however, upon rotating the indicator so as to bring both of the prongs 15 and 16 out of alinement with the axis of the latching mem- 35 ber 1, and then digitally pressing the latter inwardly, the periphery of the disk 14 will engage the other of the said cam surfaces 20, thereby moving the guard 18 back to its original position as shown in Fig. 1.

50 While I have illustrated and described the lock of my invention in a particular embodiment including a friction spring 23 and spiral spring 7, it will be evident that these and other details might be modified con- 55 siderably without departing from the spirit of my invention. Thus, the relation between the numerals at which the disk is operated may be varied by altering the relative position of the prongs 15 and 16, as shown by 60 dotted lines in Fig. 4.

I claim as my invention:

1. A keyless lock including a rotatable disk equipped with a pair of radial prongs disposed at different elevations from the 65 plane of said disk, a latching member slid-

ably mounted with respect to said disk and equipped at one end with a slot adapted to span one of said prongs to permit a sliding of the latching member to its releasing position, and a guard movable with respect to 70 said latching member and equipped with a slot normally out of alinement with the aforesaid slot, said guard and the other of said prongs equipped with coöperating cam formations coacting upon a sliding of the 75 latching member to move said guard to bring said slots into alinement, said latching member normally presenting toward the disk a shoulder adapted to engage the disk to prevent a sliding of the latching member. 80

2. A keyless lock including a rotatable disk equipped with a pair of radial prongs disposed at different elevations from the plane of said disk, a latching member slid- 85 ably mounted with respect to said disk and equipped at one end with a slot adapted to span one of said prongs to permit a sliding of the latching member to its releasing position, and with a shoulder adapted to abut against the periphery of the disk to 90 prevent such a sliding of the latching member when said slot and prong are not in alinement; and a guard movable with respect to the latching member and normally substantially closing said slot; said guard 95 and the other of said prongs equipped with coöperating cam formations coacting upon a sliding of the latching member to move said guard out of its said slot-closing position, said latching member normally presenting toward the disk a shoulder adapted to engage the disk to prevent a sliding of the 100 latching member.

3. A keyless lock including a rotatable disk equipped with a pair of radial prongs 105 disposed at different elevations from the plane of said disk, a latching member slid- 110 ably mounted with respect to said disk and equipped at one end with a slot adapted to span one of said prongs to permit a sliding of the latching member to its releasing position, and a guard pivotally mounted upon said latching member and normally sub- 115 stantially closing said slot, said guard and the other of said prongs equipped with co- 120 operating cam formations coacting upon a sliding of the latching member to move said guard out of its said slot-closing position; and spring means associated with said guard and latching member for frictionally inter- 125 locking the same to hinder a relative movement thereof.

4. A keyless lock including a shaft, a ro- 125 tatable disk carried thereby, a housing for said disk and the main portion of said shaft, a latching member extending through said housing substantially radially of said shaft and slidable with respect thereto, one end of said latching member presenting a shoulder adapted to engage the peripheral por- 130

- tion of said disk to limit the sliding of the latching member, and a guard member carried by said latching member and movable with respect thereto, said latching member 5 equipped at the end nearest said disk with a slot normally guarded by a portion of said guard member, said disk equipped with a plurality of projections extending radially thereof in different planes from that of the 10 main portion of the disk, and means carried by said guard and coöperating with one of said prongs to move said guard out of the position in which it guards said slot, thereby permitting the slotted portion of the 15 latching member to straddle the other of said prongs after the disk has been rotated to bring the last-named prong into radial alinement with the latching member.
5. A keyless lock including a rotatable 20 disk, a latching member slideable with respect thereto in a direction substantially radial of said disk and equipped at one end with a slot extending longitudinally of said latching member, a portion of said member 25 at one side of said slot being adapted to abut against the periphery of the disk to prevent an attempted sliding of said latching member out of its latching position; said disk equipped upon its periphery with a recess adapted to be entered by the said abutting portion of the latching member and with a prong adapted to enter said slot in the latching member when the said portion thereof is slid into the said recess; a guard carried by 30 said latching member and movable with respect thereto and normally substantially closing said slot; said guard and disk equipped with coöperating formations coacting, upon a sliding of the latching member, to move the guard out of its slot-closing 35 position when the disk is in one position and to return the guard to its slot-closing position upon a sliding of the latching member when the disk is in another position.
- 40 6. A keyless lock including a rotatable disk, a latching member slideable with respect thereto in a direction substantially radial of said disk and equipped at one end with a slot extending longitudinally of said 45 latching member, a portion of said member at one side of said slot being adapted to abut against the periphery of the disk to prevent an attempted sliding of said latch- 50
- ing member out of its latching position; said disk equipped upon its periphery with a recess adapted to be entered by the said abutting portion of the latching member and with a prong adapted to enter said slot in the latching member when the said portion thereof is slid into the said recess; a guard carried by said latching member and movable with respect thereto and normally substantially closing said slot, said guard and disk equipped with coöperating formations coacting, upon a sliding of the latching member, to move the guard out of its slot-closing position when the disk is in one position and to return the guard to its slot-closing position upon a sliding of the latching member when the disk is in another position; and means associated with said guard and latching member for retaining said guard in either of its said positions when moved thereto by the coaction of the said coöperating formations.
7. A keyless lock including a rotatable disk equipped with a pair of radial prongs disposed at different elevations from the plane of said disk, a latching member slideably mounted with respect to said disk and equipped at one end with a slot adapted to span one of said prongs to permit a sliding of the latching member to its releasing position, and a guard movable with respect to said latching member and normally substantially closing said slot, said guard and the other of said prongs equipped with coöperating cam formations coacting upon a sliding of the latching member to move said guard out of its said slot-closing position when the disk is turned to aline said last-named prong radially with said guard; said guard also equipped with a cam formation adapted upon a sliding of the latching member to impinge against a peripheral portion of the disk, when said disk is in another position, to return the guard to its said slot-closing position.

In testimony whereof I have signed my name in presence of two subscribing witnesses.
